ENGINE CONTROLLING APPARATUS

Romeo M. Nardone, East Orange, N. J., assignor,
by mesne assignments, to Eclipse Aviation Corporation,
East Orange, N. J., a corporation of
New Jersey

Application June 22, 1932. Serial No. 618,790

16 Claims. (Cl. 290—38)

This invention relates to engine controlling apparatus, and particularly to means for inter-relating the operation and control of the starting motor with that of other parts commonly employed in motor vehicles, such as the current generating or fuel feeding mechanism.

An object of the invention is to provide novel means operative in response to starting the engine through the aforementioned cranking instrumentality, to open the circuit to the starting motor.

In one embodiment of the invention, the circuit opening means takes the form of a servo-motor or valve preferably operated by the pressure of fuel being pumped to the carburetor; while in the second embodiment herein suggested, the circuit opening means is actuated by a centrifugal governor or driven from any convenient rotatable part of the engine.

A further object of the invention is the provision in connection with a fuel supply system for an internal combustion engine, of novel means having the dual function of controlling the quantity of fuel pumped to the carburetor, and the energization of the starting motor.

Another feature of the invention is the provision of novel means for re-energizing the starting motor whenever the engine stops or stalls, by the act of disengaging the engine driven clutch controlling the transmission of torque to the driving wheels of the propeller shaft. In this connection, a feature of the invention is the provision of means making it necessary to disengage the clutch before the circuit to the starting motor can be completed.

This feature is desirable as a safety feature in that it affords protection in case of backward rotation of the engine such as might be caused by a rolling backward of the vehicle with the engine in forward gear and the clutch engaged. Under such circumstances, the present invention operates to prevent re-engagement of the starting motor and thereby eliminates the possibility of damage to either the starting mechanism or the engine member which the starting mechanism is adapted to engage.

These and other objects and advantages to be derived from the use of the invention herein disclosed involve the inter-relation and relative functions of the parts, and will become apparent upon an inspection of the following specification and the accompanying drawing, wherein the preferred embodiment of the invention is disclosed. It is to be understood, however, that the drawing is for the purpose of illustration only and

not designed as a definition of the limits of the invention, reference being had for such purpose to the appended claims.

In the drawing,
Fig. 1 is a view partly in section and partly diagrammatic of a device embodying the invention;

Fig. 2 is a similar view of a second embodiment of the invention.

Referring to the drawing, particularly to Fig. 1, the reference character 6 designates an electric motor adapted to operate a starting mechanism of any desired character adapted to engage and impart initial rotary movement to the engine crankshaft, not shown, and reference character 7 designates a second engine shaft geared to the crankshaft to rotate therewith. On the shaft 7 there is provided an eccentric or cam 8 engageable with a cam follower 9 extending into a fuel pump 11, shown for the purpose of illustration as conforming in outline to that of a conventional pump now used in the art, having a fuel inlet 12 and an outlet 13, which as shown communicates with the engine carburetor 14 by way of the intermediate valve chamber 16 constituting part of the present invention to be described.

The starting motor 6 is shown as adapted to be energized from the battery 19, with which it has connections through suitable leads 21 and 22, the latter having a normally open break therein as indicated at 23 and 24, and adapted to be bridged by a contact plate 26, movable with, but insulated from a plunger 27 secured to a core 28 movable within an electro-magnetic device of any desired construction, the winding of which is indicated at 29 as part of the second circuit leading from the source 19 through branch conductors 31 and 32, the former of which terminates in a resilient contact member 34, and the latter in a similar resilient contact 36.

As shown, the contacts 34 and 36 are both mounted on a plate 38 extending from a bracket 39 integral with a casting 41, the said casting being herein shown as mounted to register with the upper end of the fuel pump 11 and apertured to receive a conduit 43 connecting the valve chamber 16 with the carburetor 14. Attached, as at 42 to the casting 41 is a flexible diaphragm or bellows 46, the closed end of which is secured to the closed end of a tubular sleeve or valve 47 defining the previously described valve chamber 16. As shown, the end of the tubular valve 47 is cut away to permit communication between the outlet 13 and the conduit 43 but in the normal position, as shown, the passage thus formed is a

restricted one, the edge of the valve being in position to restrict the opening in the conduit 43.

Due to the flexible nature of the diaphragm 46, the valve 47 is free to be moved to the right as viewed in Fig. 1, when the amount of fuel being pumped increases sufficiently to produce such action. The conduit 43 is then completely uncovered and in addition, the previously described switch member 34 is actuated by means now to be described. The means for actuating the switch member 34 in response to movement of the valve 47, preferably takes the form of a rod 51 secured to the end of the valve 47 by suitable means 52 and slideable to a limited extent as permitted by the collars 53 and 54 relatively to the bracket 39. As shown, the rod 51 has an insulated end 56 adapted to contact at all times the switch member 34 and effective to flex the latter to the right as viewed in Fig. 1, upon increase in the pressure 20 of the fuel within the valve chamber 16. In the position shown in Fig. 1, the switch member 34 may be contacted by the associated switch member 36, on flexing the latter to the right when the operator desires to crank the engine. In the 25 form shown such switch closure is effective through the depression of the clutch pedal 58 by which the operator disengages the clutch, not shown.

In installations wherein the switch is controlled by this means, the rock shaft 59 on which the clutch lever is mounted, is provided with an additional arm 61 to which is pivotally connected a rod 62 having telescopic engagement with a thimble portion 63 of a link 64 which in turn 35 pivotally connects with a bell crank 66, one arm 67 of which carries a finger of insulated material which engages the switch arm 36; a compression spring 71 engaging the other arm 72 of the bell crank yieldably opposes movement of the bell crank in response to actuation of the clutch lever, while the stop 74 extending upwardly from the bracket 39 limits the extent of such movement. A second stop 76, engageable with the bracket 39, limits the movement of the bell crank 40 in the opposite direction, and a second spring 75, located within the recess of the thimble 63, acts to yieldably transmit the thrust of link 62 to the link 64 to produce the switch closing action, as well as permitting limited movement of the link 62 45 relative to the link 64. Thus disengagement of the clutch may begin before, and continue after the bell crank 66 has reached the limit of its movement.

Having thus described the parts entering into the preferred embodiment of the invention as shown in Fig. 1, the operation thereof will be seen to be as follows:

When it is desired to crank the engine, the operator presses the clutch pedal 58, thus disengaging the clutch and at the same time causing the switch arm 36 to move into contact with the associated arm 34, thereby closing a circuit through the winding 29, whereupon the core 28 is drawn to the right and contacts 23 and 24 are bridged by the member 26 resulting in the energization of the winding of the motor 6, and develops a torque in the starting apparatus which is effective to turn over the engine crankshaft in the usual manner, and at the same time rotating the cam shaft 7 connected therewith. During this cranking operation, the pump 11 has only a limited capacity for pumping fuel to the carburetor 14 due to the restriction of the conduit 43 by the tubular valve 47. When the engine 75 becomes self-operating however, the sudden in-

crease in the speed of the cam shaft 7 accelerates the pump 11 to such an extent that the resulting surge of fuel ejected from the pump into the valve chamber 16 causes movement thereof to the right which movement is effective through the rod 51 to displace the switch arm 34 out of the limit of movement of the switch arm 36. Thus the circuit to the winding 29 is broken and the motor de-energized; a suitable spring or other equivalent device 25, being effective to reopen the switch 23-24 upon de-energization of the solenoid.

As long as the engine continues operating under its own power, the pressure of the fuel being pumped is sufficient to maintain the valve 47 in the open position and the switch arm 34 also in the open position. In the event however that the engine should stall, the rod 51 is returned to the position indicated in Fig. 1 by the resilient action of the bellows 46, or, if desired, an additional spring 78 may be employed for the purpose. The switch arm 34 is thus returned to the position in which it can be contacted by the arm 36, assuming the clutch pedal 58 to be in the proper, that is, depressed position.

Fig. 2 shows another embodiment of the invention wherein hydraulically operated valve 47 is replaced by a speed responsive device having a similar function so far as the control of the circuit to the electro-magnetic device 28 is concerned. In this embodiment the electrical parts are the same as in the preferred embodiment, as is also the relation of the clutch actuating mechanism thereto, except that with respect to the latter feature, the operation is simplified by the provision of a link 81 having an end portion 82 of insulating material adapted to move one of the switch arms 36' into engagement with the associated contact 34', the latter being mounted on a piece of insulating material embedded in a 105 cup-shaped collar 84 mounted on a bearing member 86 which surrounds a sleeve 87 and facilitates rotation of the latter within the collar 84, the members 87 and 84 being held for movement as a unit in the axial direction by the provision of 110 nuts 88 and 89 threaded to the members 84 and 87 respectively, and engaging opposite faces of the bearing 86. As shown, the sleeve 87 cooperates with a second sleeve 92 securely keyed to a shaft 93 which as shown is an extension of the 115 armature shaft of the generator 94 attached to a mounting plate 96 of the engine. A centrifugal link mechanism of any suitable construction as indicated at 98 connects the sleeves 92 and 87, and is effective to cause movement of the latter sleeve 120 toward the former upon acceleration of the shaft 93; such movement being opposed by a compression spring 98 which serves to return the sleeve 87 to the position indicated in Fig. 2 when the engine approaches stalling speed. In order to 125 prevent rotation of the collar 84 with the sleeve 87, a rod 99 preferably extends freely through a guide block 101, attached to the engine, which block also serves to guide the link 81.

From the foregoing it will be seen that the energization of the starting motor is first brought about through actuation of the clutch pedal 58, and is discontinued as soon as the development of self-operating power in the engine and the resulting acceleration of the shaft 93 draws the 140 sleeve 84 and contact 34' and arm 36' out of range of movement of the extension 81. In the event the engine stalls, the return of the collar 84 through the action of spring 98 again places the contact 36' in position to be moved by the 145 150

extension 81 into engagement with the contact 34', in response to a depression of the clutch pedal 58.

There is thus disclosed a novel engine controlling system wherein both the clutch and starting operations, and in one embodiment the control of the fuel supply, are inter-related for inter-dependent actuation in accordance with the requirements of the varying conditions of operation. It is to be understood, however, that in other embodiments of the invention, certain of these functions may be omitted, or the structure and interrelation of parts performing such functions may be varied, as may also the particular method herein shown of electrically and electro-magnetically controlling the energization of the starting mechanism. Likewise other changes, substitutions, additions or omissions may be made within the scope of the broadest of the appended claims.

20 What is claimed is:

1. In a control system for an internal combustion engine, a source of current supply, a motor energized from said source and operative to crank the engine, an electro-magnetic device operative to control energization of said motor, a circuit from said source to said electro-magnetic device, a single switch in said circuit, means for closing said switch, a fuel pump driven from the engine, and means responsive to actuation of said fuel pump for opening said switch.

2. In a control system for an internal combustion engine, a source of current supply, a motor energized from said source and operative to crank the engine, an electro-magnetic device operative to control the energization of said motor, a circuit from said source to said electro-magnetic device, a single switch in said circuit, a clutch actuating lever, means responsive to movement of said clutch lever for closing said switch, and means including a fluid pressure operated servo-motor for opening said switch.

3. In a control system for an internal combustion engine, a source of current supply, a motor energized from said source and operative to crank the engine, an electro-magnetic device operative to control the energization of said motor, a circuit from said source to said electro-magnetic device, a single switch in said circuit, a clutch actuating lever, means responsive to movement of said clutch lever for closing said switch, a fuel pump driven indirectly from the engine, and means responsive to actuation of said fuel pump for opening said switch.

4. In a control system for an internal combustion engine, a source of current supply, a motor energized from said source and operative to crank the engine, an electro-magnetic device operative to control energization of said motor, a circuit from said source to said electro-magnetic device, a single switch in said circuit, a clutch actuating lever, means responsive to movement of said clutch lever for closing said switch, and speed responsive means for opening said switch.

5. In a control system for an internal combustion engine, a source of current supply, a motor energized from said source and operative to crank the engine, a circuit controlling energization of said motor, a single switch in said circuit, means for closing said switch, a fuel pump driven from the engine, and means responsive to actuation of said fuel pump for opening said switch.

6. In a control system for an internal combustion engine, a source of current supply, a motor energized from said source and operative to crank the engine, a circuit controlling energization of

said motor, a single switch in said circuit, a clutch actuating lever, means including a reciprocable rod responsive to movement of said clutch lever for closing said switch, speed responsive means for moving said switch out of the range of action of said switch closing means, said speed responsive means including a switch carrying collar aligned with said rod, and common guide means for said collar and rod.

7. In a control system for an internal combustion engine, a source of current supply, a motor energized from said source and operative to crank the engine, a circuit controlling energization of said motor, a single switch in said circuit, a clutch actuating lever, means responsive to movement of said clutch lever for closing said switch, speed responsive means for opening said switch, said speed responsive means including a rotating and axially movable sleeve, a collar movable axially with said sleeve, and carrying both contacts of said switch, a guide block adjacent said switch contacts, and means extending through said guide block for closing said contacts and preventing rotation of said collar on said sleeve.

8. In a control system for internal combustion engines, a source of current supply, a motor energized from said source and operative to crank the engine, a circuit controlling energization of said motor, a single switch in said circuit, a clutch actuating lever, means responsive to movement of said clutch lever for closing said switch, speed responsive means for opening said switch, said speed responsive means including a rotating and axially movable sleeve, a collar movable axially with said sleeve and carrying both contacts of said switch, a guide block adjacent said switch contacts, and means extending through said guide block for closing said contacts when said sleeve is within a predetermined axial position only.

9. In a control system for an internal combustion engine, a source of current supply, a motor energized from said source and operative to crank the engine, an electro-magnetic device operative to control the energization of said motor, a circuit from said source to said electro-magnetic device, a single switch in said circuit, means for closing said switch, means including a fluid pressure operated servo-motor for opening said switch, a fuel pump driven from the engine crank-shaft, a carburetor fed from said fuel pump, and means including said servo-motor for governing the quantity of fuel supplied by said pump to said carburetor.

10. In a control system for an internal combustion engine, a source of current supply, a motor energized from said source and operative to crank the engine, an electro-magnetic device operative to control energization of said motor, a circuit from said source to said electro-magnetic device, a single switch in said circuit, means for closing said switch, means including a fluid pressure operated servo-motor for opening said switch, a fuel pump driven from the engine crankshaft, a carburetor fed from said fuel pump, a conduit connecting said carburetor and said pump, and a valve in said conduit, said valve constituting part of said servo-motor.

11. In combination with an internal combustion engine having a fuel pump and a carburetor, a conduit connecting said pump and carburetor, a valve controlling the rate of flow through said conduit, said valve being movable in response to the pressure of the fuel being pumped, a motor for starting said engine, and means actuated by said valve for de-energizing said starting motor.

12. In combination with an internal combustion engine having a carburetor and a fuel pump, a conduit connecting said pump and carburetor, a valve controlling the rate of flow through said conduit, said valve being movable in response to the pressure of the fuel being pumped, a motor for rotating said engine, means actuated by said valve for de-energizing said starting motor, a circuit controlling energization of said starting motor, and a switch in said circuit, said switch being operated by said valve. 80
13. In combination with an internal combustion engine having a carburetor and a fuel pump, a conduit connecting said pump and carburetor, a valve controlling the rate of flow through said conduit, said valve being movable in response to the pressure of the fuel being pumped, a motor for rotating said engine, a clutch driven by said engine, means movable with said clutch to energize said starting motor, means actuated by said valve for de-energizing said starting motor, a circuit controlling energization of said starting motor, and a switch in said circuit, said switch being operated by said valve. 85
14. In a control system for an internal combustion engine, a source of current supply, a motor energized from said source and operative to crank the engine, a circuit controlling energization of said motor, a single switch in said circuit, a clutch actuating lever, means including a reciprocable rod responsive to movement of said clutch lever for closing said switch, speed responsive means for moving said switch out of range of said switch closing means, said speed responsive means including a switch carrying collar aligned with said rod, a second rod extending from said collar and a guide block adapted to receive both said rods and thereby prevent rotation of said collar. 90
15. In a control system for an internal combustion engine, a source of current supply, a motor energized from said source and operative to crank the engine, a circuit controlling energization of said motor, a single switch in said circuit, a clutch actuating lever, means including a reciprocable rod responsive to movement of said clutch lever for closing said switch, speed responsive means for moving said switch out of range of said switch closing means, said speed responsive means including a switch carrying collar aligned with said rod, a second rod extending from said collar and a guide block adapted to receive both said rods and thereby prevent rotation of said collar. 95
16. In a control system for an internal combustion engine, a source of current supply, a motor energized from said source and operative to crank the engine, an electro-magnetic device operative to control the energization of said motor, a circuit from said source to said electro-magnetic device, a single switch in said circuit, a clutch actuating lever, means responsive to movement of said clutch lever for closing said switch, and engine responsive means for moving said switch out of range of action of said switch closing means. 100
